(57) **CLAIM**

We claim the ornamental design for a ganging tray, as shown and described.

DESCRIPTION

FIG. 1 is a front perspective view of a ganging tray, showing our new design;

FIG. 2 is a rear perspective view of the ganging tray thereof;

FIG. 3 is a bottom perspective view of the ganging tray thereof;

FIG. 4 is a right side view of the ganging tray thereof, the left side view is a mirror image of the right side view of FIG. 4;

FIG. 5 is a front view of the ganging tray thereof;

FIG. 6 is a rear view of the ganging tray thereof;

FIG. 7 is a top view of the ganging tray thereof;

FIG. 8 is a bottom view of the ganging tray thereof;

FIG. 9 is a cross-sectional view along lines IX-IX of FIG. 5;

FIG. 10 is a cross-sectional view along lines X-X of FIG. 5;

FIG. 11 is a cross-sectional view along lines XI-XI of FIG. 5; and,

FIG. 12 is a cross-sectional view along lines XII-XII of FIG. 5.

1 Claim, 10 Drawing Sheets
